COMBINATION SUB-FLOOR AND TOP FLOOR

Clarence U. Gramelspacher, Jasper, Ind., assignor to Jasper Wood Crafters, Inc., Jasper, Ind.

Application March 21, 1957, Serial No. 647,577

9 Claims. (Cl. 20—8)

This invention pertains to wood flooring and in particular to laminated wood flooring and more specifically still to flooring in the form of a combination sub-floor and top floor.

In the laying of floors in a building, such as a residence structure, it is customary to lay sub-flooring on the joists and then to apply the top flooring on top of the sub-floor. This arrangement is generally satisfactory so long as the flooring remains tight but there is a tendency to work loose and squeak after a period of time. Further, the laying of sub-flooring and then the subsequent laying thereon of top flooring represents two complete and independent operations thus involving the expenditure of considerable time and labor. In any case where top flooring is laid separately from the sub-flooring it is necessary to carry out extensive finishing operations on the floor in order to bring the surface to the desired finished condition.

Having the foregoing in mind, the primary object of the present invention is to provide a floor member to be laid on joists of a building to form the floor thereof and which member comprises as an integral unit both the sub-floor and top floor.

Another object of the invention is the provision of a wood panel of substantial size consisting of integrally joined top floor and sub-floor that can be laid directly on the joists of a building to make up the flooring thereon.

A still further object of the invention is the provision of a combination sub-floor and top floor unit for being laid in the joists of a building to make up the floor thereof on which squeaking of the floors is entirely eliminated.

A still further object of this invention is the provision of a panel member that can be laid on the joists of a building making up a floor which can be applied to sub-flooring and which panel member is sealed and which will remain tight and squeak-proof for a long period.

A further object of the present invention is the provision of a factory constructed floor panel having in combination sub-flooring and finished top flooring integrally secured to the sub-floor so that the member can be laid on the joists of a building to make up a complete sealed tight floor in a single operation.

A further object of the present invention is the provision of an arrangement for laying floors in buildings such that factory finished panels can be employed thereby making it possible to create a variety of different floor patterns without the great expense that accompanies the creation of such patterns in the floor at the time it is laid.

Another object of this invention is the provision of a tongue and groove type floor panel of substantial size which can be placed directly on the joists of a building to make up the entire floor thickness thereof and with the panels being of sufficient area that the floor lays up very quickly thus eliminating a great deal of the labor ordinarily associated with such a work operation.

These and other objects and advantages will become more apparent upon reference to the accompanying drawings in which:

Figure 1 is a perspective view showing, somewhat dia-

2

grammatically, a floor panel according to my invention;

Figure 2 is a perspective view similar to Figure 1 but showing the top and intermediate panels cut back to show the manner in which the three thicknesses of the panel of Figure 1 inter-fit.

Figure 3 is a sectional view through the floor portion of a building showing the joists and the manner in which a panel according to the present invention lays up thereon.

Figure 4 is a perspective view showing the manner in which the present invention could be adapted for forming a two-ply flooring panel to be laid on a conventional sub-floor;

Figure 5 is a view like Figure 1 but shows the top floor in the form of strips rather than blocks;

Figure 6 is a plan view showing a panel somewhat like that illustrated in Figure 1 except with the individual blocks of the panel being formed of small strips to form a parquet surface effect.

Figure 7 is a sectional view indicated by line 7—7 of Figure 1 showing the individual plies of the surface sections of the floor panel.

Referring to the drawings somewhat more in detail the floor panel illustrated in Figure 1 comprises a bottom section 10, an intermediate section 12, and a top section 14. Bottom section 10 is of ply-wood as is also intermediate section 12. The top section 14 is also composed of plywood but is in the form of individual rectangular blocks 16 having a hard wood upper facing suitable for a floor surface and finished smooth and with adjacent blocks 16 laid, preferably, so that they are respectively at right angles.

It is preferred that the three layers be of the same overall dimensions and this enables the top and bottom layers to be arranged in exact vertical alignment with each other while the intermediate layer or section 12 is off-set longitudinally and laterally thereby forming a tongue on two adjacent edges of the panel and a corresponding groove on the other two adjacent edges.

The plies making up the sections 10, 12 and 14 may vary considerably as to the make up but a preferred arrangement is to have the bottom-most ply of section 10 of substantial thickness and to have the top-most ply of section 14 of substantial thickness. This provides for ample material for finishing both faces of the panel.

The entire panel may vary in thickness although it is preferred that it be no thinner than $\frac{3}{4}$ " and it may be $1"$ to $1\frac{1}{2}$ " depending on the requirements of the builder.

The actual arrangement of the different sections of the panel of Figure 1 and the approximate relative thickness of the plies therein will more clearly be seen in Figure 7 which is a section through one edge of panel of Figure 1 in somewhat enlarged scale. This view also shows the groove 18 that extends about two edges of the panel and which may advantageously be somewhat tapered on the top to receive the tongue of the next adjacent panel which may similarly be somewhat tapered on the top surface to match the tapered surface of the tongue.

As will be seen in Figure 2 the three sections of floor panels are connected by conventional gluing methods by applying an adhesive 20 between the layers and then pressing them together and permitting the adhesive to set.

The panel of Figure 1 is made up of three sections, but it will be evident that the panel could consist of merely two sections as shown in Figure 4 and be laid on sub-flooring 22. The backing of the panel is indicated at 24 and comprises plywood and the top floor at 26 may be made up of panels of any suitable type and these may be plywood also or may consist of individual strips of flooring wood as illustrated. As in the case of the

panel of Figure 1 panels 24 and 26 are preferably set up to provide a tongue and groove effect for interlocking the adjacent panels and provide for a sealing overlap therebetween.

Figure 5 illustrates a panel like Figure 1 except the top floor 28 thereof is in the form of strips and which strips may be the entire thickness of the top section of the panel, or may comprise veneer strips forming the top ply of the plywood making up the top section of the panel.

Figure 6 shows a still further modified panel arrangement in which the top face of the panel presents a parquet surface effect by means of parquet blocks 30 arranged on a backing similar to the previously described panel arrangements.

A feature of the present invention resides in the fact that a panel of substantial size when glued up in the manner described and illustrated, tends to warp so as to be concave upwardly. This effect will be noted in Figures 1 and 5 and in Figure 3 it will be seen how the panel appears when put in place on the floor but before it is nailed to the joists.

The showing in Figure 3 illustrates a plurality of adjacent joists 31 and at the extreme right side of the view is the left edge of a panel 32 fixed in place on the joists. Leftwardly of panel 32 is a panel 34 receiving in its groove 36 the tongue at the left edge of panel 32. It will be noted that panel 34 curves upwardly before being fixed in position against the joists. When the panel 34 is pulled down into the position indicated by the dot-dash outline 38 it will be flat and press against the joists from one edge to the other thereby eliminating squeaking and cracking of the flooring. The panels may be nailed in place or there may be an adhesive applied between the joists and the panels or both may be employed in order to arrive at a particularly permanent and tight structure. It will be evident that the floor panels could be laid on sub-flooring if so desired with the advantage obtaining that all nails in the panels could be invisible with a suitable adhesive connecting the panels to the sub-flooring.

I claim:

1. In a floor panel; a plywood surface layer having its upper ply of substantial thickness and of hardwood, a core layer applied to the back of said surface layer and off-set therefrom in two directions and adhesively connected to the top layer, and a backing layer in alignment with the top layer and adhesively bonded to the back of said core layer whereby integral tongues and grooves are formed about the panel, and said panel being characterized in that it is at least slightly concave upwardly whereby it bears against joists on which it is laid up with sufficient pressure to prevent squeaking and cracking.

2. In a floor panel; a plywood surface layer having its upper ply of substantial thickness and of hardwood, a core layer applied to the back of said surface layer and off-set therefrom in two directions and adhesively connected to the top layer, and a backing layer in alignment with the top layer whereby integral tongues and grooves are formed about the panel, and said panel being characterized in that it is at least slightly concave upwardly whereby it bears against joists on which it is laid up with sufficient pressure to prevent squeaking and cracking, the said upper ply of the top layer being made up of blocks with the grain of adjacent blocks at respectively right angles to each other.

3. In a floor panel; a plywood surface layer having its upper ply of substantial thickness and of hardwood, a core layer applied to the back of said surface layer and off-set therefrom in two directions and adhesively connected to the top layer, and a backing layer in alignment with the top layer whereby integral tongues and grooves are formed about the panel, and said panel being characterized in that it is at least slightly concave upwardly whereby it bears against joists on which it is laid up with sufficient pressure

to prevent squeaking and cracking, at least the top ply of the upper layer of the panel being formed of strips extending the length of the panel.

4. In a floor panel; a plywood surface layer having its upper ply of substantial thickness and of hardwood, a core layer applied to the back of said surface layer and off-set therefrom in two directions and adhesively connected to the top layer, and a backing layer in alignment with the top layer and adhesively bonded to the back of said core layer whereby integral tongues and grooves are formed about the panel, and said panel being characterized in that it is at least slightly concave upwardly whereby it bears against joists on which it is laid up with sufficient pressure to prevent squeaking and cracking, at least the top layer of the upper layer of the panel being formed of narrow strips laid up in a block pattern.

5. In a floor panel; a plywood surface layer having its upper ply of substantial thickness and of hardwood, a core layer applied to the back of said surface layer and off-set therefrom in two directions and adhesively connected to the top layer, and a backing layer in alignment with the top layer and adhesively bonded to the back of said core layer whereby integral tongues and grooves are formed about the panel, and said panel being characterized in that it is at least slightly concave upwardly whereby it bears against joists on which it is laid up with sufficient pressure to prevent squeaking and cracking, at least the top layer of the upper layer of the panel being formed of narrow strips laid up in parquet pattern.

6. In a building structure; spaced floor joists, and floor panels laid up on the floor joists and forming the floor, said panels being of substantial size and comprising a plurality of layers of plywood integrally bonded together, and said panels being characterized in being at least slightly concave upwardly before being fixed to the joists.

7. In a building structure; spaced floor joists, and floor panels laid up on the floor joists and forming the floor, said panels being of substantial size and comprising a plurality of layers of plywood integrally bonded together, and said panel being characterized in being at least slightly concave upwardly before being fixed to the joists, said panels having inter-engaging tongues and grooves about the edges.

8. In a building structure; spaced floor joists, and floor panels laid up on the floor joists and forming the floor, said panels being of substantial size and comprising a plurality of layers of plywood integrally bonded together, and said panel being characterized in being at least slightly concave upwardly before being fixed to the joists, said panels having a surface ply of substantial thickness and of hardwood whereby the panel can be finished in a conventional manner after being laid up on the joists.

9. A method of flooring a building having joists which comprise; preparing floor panels of a substantial area so that the panels will span a plurality of spaces between the joists, forming said panels so as to be concave upwardly, and fixing the panels to the joists so that the panels are flat and thus bear down on the joists between the edges of the panels thereby preventing squeaking and cracking of the floor, said method also including the step of overlapping the edges of panels whereby the panels are sealingly inter-fitted.
